(57) CLAIM

The ornamental design for a cosmetic box, as shown and described.

DESCRIPTION

FIG. 1 is a perspective from above of a cosmetic box showing my new design according to one embodiment; FIG. 2 is a front view of the cosmetic box of FIG. 1; FIG. 3 is a right side view of the cosmetic box of FIG. 1; FIG. 4 is a left side view of the cosmetic box of FIG. 1; FIG. 5 is a rear view of the cosmetic box of FIG. 1; FIG. 6 is a top view of the cosmetic box of FIG. 1; FIG. 7 is rear perspective from above the cosmetic box of FIG. 1;

FIG. 8 is a perspective view from above of a cosmetic box showing my new design according to another embodiment; FIG. 9 is a front view of the cosmetic box of FIG. 8; FIG. 10 is a right side view of the cosmetic box of FIG. 8; FIG. 11 is a left side view of the cosmetic box of FIG. 8; FIG. 12 is a rear view of the cosmetic box of FIG. 8; FIG. 13 is a top view of the cosmetic box of FIG. 8; and, FIG. 14 is rear perspective from above the cosmetic box of FIG. 8.

The broken lines shown along the rear of the cosmetic box illustrate portions of the cosmetic box and form no part of the claimed design.

The bottom view of the cosmetic box forms not part of the claimed design.

In the embodiment shown in FIGS. 8-14, the cosmetic box is shown with a symbolic break in length. The appearance of any portion of the article between the break lines forms no part of the claimed design.

1 Claim, 8 Drawing Sheets
